 Dorman

[57] CLAIM

The ornamental design of a combined toy gun and projectile therefor, as shown and described.

DESCRIPTION

FIG. 1 is a front perspective view of a combined toy gun and projectile therefor showing my new design, the side opposite being substantially a mirror image;

FIG. 2 is an inverted perspective view of the combined toy gun and projectile therefor of FIG. 1 with the projectile in a seated condition;

FIG. 3 is a front perspective view of a modified form of a combined toy gun and projectile therefor, the side opposite being substantially a mirror image, and

FIG. 4 is an inverted perspective view of the toy gun and projectile therefor of FIG. 3 with the projectile in a seated condition.

FIG. 3
